DESIGN FOR AN ELECTRIC LIGHTING FIXTURE

Martin W. Schwartz and Max J. Marks,
Chicago, Ill.

Application November 12, 1946, Serial No. 134,710

Term of patent 14 years

(Cl. D48—23)

To all whom it may concern:

Be it known that we, Martin W. Schwartz and Max J. Marks, citizens of the United States and residents of Chicago, in the county of Cook and State of Illinois, have invented a new, original, and ornamental Design for an Electric Lighting Fixture, of which the following is a specification, reference being had to the accompanying drawing, forming a part thereof.

In the drawing,

Fig. 1 is a perspective view of an electric lighting fixture, showing my new design.

Fig. 2 is a fragmentary side elevation of one end of the fixture shown in Figure 1; and

Fig. 3 is a cross sectional view of the fixture taken on line 3—3 in Figure 1.

We claim:

The ornamental design for an electric lighting fixture, as shown.

MARTIN W. SCHWARTZ.
MAX J. MARKS.
